PETER CODINA, OF HOBOKEN, NEW JERSEY, ASSIGNOR TO MIR, CODINA & MARQUES, OF HOBOKEN, NEW JERSEY, A FIRM.

CORK-CUTTING MACHINE.

1,109,966.

Specification of Letters Patent. Patented Sept. 8, 1914.

Application filed December 4, 1913. Serial No. 804,719.

To all whom it may concern:

Be it known that I, PETER CODINA, a subject of the King of Spain, residing at Hoboken, in the county of Hudson and State of New Jersey, have invented a certain new and useful Improvement in Cork-Cutting Machines, of which the following is a full, clear, and exact description.

The object of this invention is to provide a machine by means of which corks or stoppers of various kinds and sizes, and for various purposes, may be cut accurately, with great rapidity, and with a utilization of the bark without waste.

The invention comprises a cork cutting machine in which the bark in strips of a width equal to the length of the cork, is exposed to the cutting action of a punch or cutter and intermittently fed into position to be so acted upon by the punch or cutter as the latter is caused to be both reciprocated and rotated; and the invention also includes a strip trimming mechanism operative while the strip is passing through the machine to render available the remaining good parts of the punched strip for the production of disk and such like stopper or closure elements, all as I will proceed now to explain and finally claim.

In the accompanying drawing illustrating the invention, in the several figures of which like parts are similarly designated, Figure 1 is a top plan view of a machine embodying the invention. Fig. 2 is a side elevation looking in the direction of the arrow, Fig. 1, with a part of one of the bearings for the mandrel broken away. Fig. 3 is a front elevation. Fig. 4 is a cross-section on a larger scale taken on the line A B, Fig. 2. Fig. 5 is a cross-section taken on line C D, Fig. 2, and looking toward the right, and Fig. 6 is a cross-section on the line E F, Fig. 2, looking toward the left, showing the feed mechanism. Fig. 7 is a longitudinal section of the punch or cutter and its mandrel, showing the ejector in elevation. Fig. 8 is a face view of the combined work-guide and punch-block. Fig. 9 is a perspective view illustrating some of the operations on the cork bark that are within the capability of the machine.

Without thereby limiting the invention or its adaptability, I will proceed to describe the same as illustrated in the drawings:

1 may represent a bed-plate, mounted

upon suitable legs or frames 2. Erected on the bed-plate are bearing-pieces 3 in which is mounted a shaft 4 provided with fast and loose pulleys 5 and 6, in connection with which is any ordinary belt shifter 7 operated by a lever 8 pivoted beneath the bed-plate. On this shaft 4 is also mounted a cam 9 for imparting a reciprocating motion to the punch or cutter mandrel as presently described; and also on this shaft is mounted a crank-disk 10 to operate the main feed shaft as presently described.

As shown more in detail in Fig. 7, the punch or cutter mandrel or shaft 11 is hollow or tubular, and it is provided in any suitable way with the tubular punch or cutter 12 which acts upon the strip of bark to punch out the corks. Within this hollow mandrel is arranged a stationary rod or pusher 13 which acts upon a movable rod or ejector 14 having the head 15 of substantially the internal diameter of the punch. The rod 13 is adjustably fixed in a standard 16, as by means of a set-screw 17. The mandrel 11 is mounted in the bearings 18 and 19, erected on the bed-plate 1, and is provided with a pulley 20, or any other means, for imparting to it an independent rapid rotation; and said shaft is provided with a pin collar 21 loose thereon and held in place lengthwise of the shaft by collars 22, and this pin collar is engaged by a fork 23 slidingly mounted in a lever 24 pivoted at 25 to a bracket 26 extending from one side of the bed-plate, and said lever 24 has a roller connection 27 with the cam 9 so as to impart a longitudinal reciprocation to the mandrel as the cam is rotated.

The bearings 18 and 19 receive a vertically adjustable cross-head 28 mounted upon an adjusting screw 29, which in turn is mounted in the bed-plate, so that said cross-head may be moved vertically up and down in the bearings. This cross-head carries the bearing-blocks 30, and in these bearing-blocks is mounted the feed-shaft 31, said feed-shaft being located immediately below and in vertical alinement with the mandrel 11 and parallel therewith. At one end of the feed shaft 31 is a ratchet wheel 32 keyed to said shaft by means of a key 33 mounted in a longitudinal key-way or seat 34 in said shaft, so that said shaft may be adjusted longitudinally in its bearings and in the ratchet wheel. Loosely mounted on the shaft 31 is

an arm 35 carrying a pawl 36 which is connected by a rod 37 with the crank-disk 10 on the driving shaft 4 in such way that the feed-shaft is given an intermittent rotary motion. This rod is adjustably mounted on the crank-disk, and also may be provided with a turnbuckle 38 so as to vary the throw. The ratchet wheel 32 may be engaged by a spring dog 39 to prevent back-motion.

10 Any suitable means may be used to lock the cross-head and feed-shaft in adjusted position, as for example, the set-screw 40.

The forward end of the feed-shaft is mounted in a bearing-block 41 which in turn is housed in a housing 42 on an arm 43 adjustably mounted upon a slide 44 arranged in ways 45 on the bed-plate. The bearing-block is held in place on the shaft by means of a collar 46 on one side and a gear wheel 47 on the opposite side of the block, said collar and gear wheel being fast on the shaft. At the front end of the shaft is fixed a stock feed roller 48 adapted to engage the underside of the stock in line with the mandrel 49 and its cutter. The gear wheel 47 meshes with a pinion 49 on a short shaft 50 mounted in a bearing 51 on the arm 43, and a bearing in the post 52 rising from a laterally extended arm 53 on the base 54 of the arm 43, and this pinion 49 is connected and turns with a bevel gear 55 which meshes with a bevel pinion 56 mounted on a vertically disposed shaft 57. This shaft 57 is stepped in the post 52, and has a bearing in a head 58 on an arm 59 extending up from the arm 43. This headed arm will be of such design and structure as to afford adequate support for the parts it sustains. In the construction shown it is found advisable to add the lateral brace 60.

61 is a shaft arranged parallel to the shaft 57 and stepped in the arm 53 and likewise having a bearing in the head 58. These two shafts 57 and 61 are connected to turn in the same direction by means of the gears 62, 63 and 64, so that motion imparted to the shaft 57 by the bevel gears and the feed-shaft 31 may be transmitted to the shaft 61. These shafts 57 and 61 are provided with the feed wheels 65 and 66, formed integrally with hubs and preferably arranged in pairs, with the feed elements or teeth of each pair staggered, (see Figs. 5 and 6) and the two pairs out of horizontal alignment, in order to insure an extensive grip upon the work to be fed. These feed elements may be and are here shown as teeth, such as are common in gear wheels. If desired, these feed wheels may be made adjustable on their respective shafts, by means of the set-screws 67 and 68, or by any other suitable means. These peculiarities in the construction and arrangement of the feed wheels are designed to meet the varying conditions that are encountered in the stock, such as irregularity

in grain, or texture, differences in surface contour, and degrees of hardness.

The gear wheels 47 and 49 may have teeth of sufficient length to admit of a limited vertical adjustment of the feed shaft 31 by means of the cross-head 28 and its adjusting screw 29. Additional elevation may be given to it by introducing a shim or packing between the base 54 of the arm 43 and its slide 44.

In order to adjust the feed mechanism to the work horizontally, the feed shaft is capable, as already indicated, of a longitudinal movement in its bearings, and this is effected by the engagement of the bearing-block 41 with the arm 43, and the imparting to said arm of a longitudinal movement to its slideways 45. Any suitable means, such as an adjusting screw 69 fixed to the bed-plate 1, may be used for effecting this movement.

The work-receiving table may comprise a horizontal bed 70, a vertical flange 71, and a shank 72, which last is adjustably mounted in a stand 73 and fixed in such adjustment by any suitable means, such as a set-screw 74. This stand is adjustably mounted upon the base 54, as by means of a slot and screw 75, so that the work table may be set up relatively to the feed wheels.

76 is a combined work-guide and punch-block, adjustably mounted in a bracket 77 fixed to the frame, and held in such adjustment by any suitable means, such as a set-screw 78. This device 76 may have in its face a friction roller 79, and also preferably has the punch-block or die 80 arranged therein to receive the impact of the punch or cutter so as to prevent damage to the cutting edge, and for this purpose this block 80 may be of any relatively soft material, such as a soft metal. The arm 43 thus becomes a carrier for the stock or work-feeding mechanism.

The complementary work-supporting end 81 is mounted upon an arm 82 pivoted in a stand 83 rising from the bed-plate, and this arm may be counterweighted so as to facilitate the shifting of the upper roller 81 when access is to be had to the work, and for convenience in operating this roller, its shaft on which it turns freely, may be extended laterally in the form of a handle 84. The upper end of the stand 83 in which the roller arm 82 is pivoted, has a trough-like formation so as to prevent side walls 85 to hold the roller in alignment with its companion roller 48 so that it may engage the upper side of the stock in line with the mandrel and cutter. The elevation of this roller 81 may be adjusted by the set-screw 86 arranged in it and bearing against the stand 83.

A vertically arranged shield 87 is placed at the rear of the punch-block and may be

conveniently fastened to the head 58, as shown in Figs. 5 and 6, and this shield is provided with a hole 88 in the path of travel of the punch and through which the punch 5 passes in cutting the cork. This shield may be provided with the vertically disposed friction roller 89 to relieve friction of the stock. The objects of the shield are to prevent the ejected corks from flying away and 10 from falling on the machine, to guide them into the chute next described, and to safeguard the operator from the cutter. To this shield is fastened a chute 90 which extends through an opening 91 in the bed-plate 15 to receive and discharge the corks as they are ejected from the punch.

In order to keep the punch clean and oiled, a swab 92 may be mounted upon an arm 93 fixed to the bearing 18.

The machine as so far described is adapted to act upon a strip of cork bark cut to a width equal to the length of cork desired. Such a strip is placed in the work-holder with its outside or back uppermost. Power 25 being applied to the machine, the punch mandrel is given a rotary and longitudinally reciprocating motion, and the punch bores through the work and is then retracted, and on the back movement the ejector is brought 30 into operation to eject the cut cork, and then the feed wheels become active to feed the work forward for the next cut. The feed of the work is, of course, essentially a friction feed, and such feed is arrested during 35 the moment of time the cutter is passing into and out of the work by means of the intermittent ratchet feed previously described. The rollers 48 and 81 are practically work supports for supporting the 40 work after it leaves the work-holder, and at the time it is being punched, and the upper roller 81 is of sufficient weight to act as a hold-down or presser for the work.

I have shown the headed ejector 14—15 as 45 separate from the actuating rod 13, but in practice the suction caused by the rapidity of motion, prevents the dislodgment of the device from the punch.

Where the stock or bark is of greater 50 thickness than sufficient to form the desired size of cork, and yet contains enough valuable cork for the manufacture of the disks that are largely used in bottle stoppers of the cap variety, the stock may be prepared 55 for the subsequent cutting of such cork disks by trimming off the outer rough portion or back, as indicated in Fig. 9, thereby leaving a thickness sufficient to form such cork disks. For the purpose of thus preparing 60 the stock while it is being punched for cylindrical corks, I provide a rotary circular cutter 94, such as a knife or saw, mounted on a vertical shaft 95, which is driven in any suitable manner, as by means of a belt 65 96 engaging a pulley 97 on the shaft 95 and

a pulley 98 on a shaft 99 erected on the bearing 3, for example, and driven by bevel gearing 100 from the shaft 4. Any suitable belt tightener, automatic or otherwise, indicated at 101, may be used to keep the belt 70 taut. The rotary cutter 94 may be mounted upon its shaft 95 to turn therewith, in any suitable way, by which it may be adjusted with relation to the punch or cutter 12 to cut the stock to the desired level outside of the spaces formed by cutting out the corks, and I have shown it so adjustable by a screwthread arrangement comprising the screwthread 102 on the shaft, and the adjusting nuts 103 and 104. 75

A stock or work support 105 is arranged opposite the cutter to take the thrust of the cutter, and this support may be mounted upon an arm 106 adjustably secured to the stand 83, so as to be capable of being adjusted correspondingly with the table 70. 80

The shaft 95 may be stepped in an arm 107, projecting from the base of the stand 83, and this stand may be adjusted in ways 108 on the bed-plate by means of a suitable 90 adjusting screw 109. By this adjustment also, the upper roller 81 may be kept in alignment with the lower roller 48.

Variations in the details of construction and arrangement of parts are within the 95 principle of the invention, and the scope of the claims hereinafter made.

What I claim is:—

1. In a cork cutting machine, the combination of a main shaft, a feed shaft, connections between said main shaft and feed shaft to intermittently rotate said feed shaft, a mandrel, a cutter carried by said mandrel, means to reciprocate said mandrel lengthwise, independent means to rotate 100 said mandrel, a feed roller mounted on and turning with the feed shaft and adapted to engage the stock on its underside in line with said mandrel and cutter, a complementary gravity feed roller adapted to engage 105 the stock on its upper side in line with the mandrel and cutter, feed wheels arranged at right angles to the axes of the feed rollers and adapted to engage one side of the work or stock in advance of the feed rollers, a 110 work or stock supporting mechanism adapted to support the work or stock against the thrust of the mandrel and the action of said feed wheels, and means to drive the feed wheels from the feed shaft. 115

2. In a cork cutting machine, the combination of a main shaft, a feed shaft arranged parallel with the main shaft, connections between said shafts for intermittently rotating said feed shaft, a mandrel 125 arranged above and in parallelism with the feed shaft, a punch or cutter carried by said mandrel, means connecting said main shaft and mandrel to reciprocate the mandrel lengthwise, independent means to rotate the 130

mandrel, a suitable work or stock supporting mechanism, including a pair of rollers engaging the upper and lower sides of the stock in line with said mandrel and its cutter, a pair of feed wheel shafts, feed wheels thereon adapted to engage one side of the stock in advance of the cutter and supporting rollers, means connecting the pair of feed wheel shafts to cause them to turn in the same direction, and gearing interposed between the main feed shaft and one of the feed wheel shafts to actuate said pair of feed wheel shafts.

3. In a cork cutting machine, the combination of a main shaft, a mandrel and a cutter thereon, stationary bearings for said mandrel, a main feed shaft arranged below and in vertical alignment with the mandrel, a vertically adjustable cross-head in which said feed shaft is mounted and by which its elevation may be varied, a gear wheel fixed to one end of said feed shaft, means on the other end of said feed shaft connected with the main shaft by which the feed shaft may be given an intermittent rotation, means connected with the main driving shaft for varying the speed of the feed shaft, a work or stock feeding mechanism, and a horizontally adjustable carrier for said work or stock feeding mechanism.

4. In a cork cutting machine, the combination of a main driving shaft, a rotary reciprocating cutter mandrel arranged in fixed bearings, a main feed shaft arranged below and in parallelism with the cutter mandrel, a vertically adjustable cross-head in which said feed shaft is supported and adjustable longitudinally, a horizontally adjustable arm, a bearing therein for said feed shaft in which it is fixed against independent longitudinal movement, the adjustment of the arm serving to adjust the feed shaft longitudinally, work or stock feed wheels mounted in said horizontally adjustable arm, a gear wheel on the main feed shaft, and transmission gearing also carried by the adjustable arm, including a gear wheel meshing with the gear wheel on the main feed shaft and transmitting the intermittent motion of the main feed shaft to the work or stock feed wheels and permitting independent adjustment of the main feed shaft and the work or stock feed wheels.

5. In a cork cutting machine, the combination of a driving shaft, a cutter mandrel mounted in fixed bearings, means driven from the main shaft for reciprocating the cutter mandrel, independent means for rotating said mandrel, a main feed shaft arranged below and in parallelism with the cutter mandrel, means actuated by the main shaft for imparting an intermittent step-by-step motion to the said feed shaft, a feed roller mounted on said feed shaft and engaging the underside of the stock in line

with the cutter, a gear wheel connected with and driven by the feed shaft, a pair of work or stock feeding wheels adapted to engage one side of the stock in advance of the cutter and said feed roller, shafts therefor, gearing interposed between one of said feed wheel shafts and the gear wheel on the main feed shaft, and means to connect the pair of feed wheel shafts to cause them to turn in the same direction.

6. In a cork cutting machine, the combination of a driving shaft, a cutter mandrel mounted in fixed bearings, means driven from the main shaft for reciprocating the cutter mandrel, independent means for rotating said mandrel, a main feed shaft arranged below and in vertical alignment with the cutter mandrel, means actuated by the main shaft for imparting an intermittent step-by-step motion to the said feed shaft, a gear wheel fixed on and driven by the feed shaft, a pair of stock or work feeding wheels adapted to engage the side of the stock in advance of the cutter, shafts therefor, gearing interposed between one of said feed wheel shafts and the gear wheel on the main feed shaft, means to connect the pair of feed wheel shafts to cause them to turn in the same direction to feed the stock toward the cutter, an adjustable arm engaging the main feed shaft and supporting the feed wheel shafts and adapted to adjust the main feed shaft longitudinally, a feed roller fixed to and turning with the main feed shaft and engaging the underside of the stock in line with the cutter, a complementary gravity feed roller engaging the upper side of the stock in line with the cutter, a bearing piece in which the gravity feed roller is supported above the feed roller on the main feed shaft, and means to effect the adjustment of said bearing piece to maintain the alignment of the said feed rollers.

7. In a cork cutting machine, the combination of a cutting mechanism, and a work or stock feeding mechanism, with work or stock supporting means, comprising a vertically and horizontally adjustable table arranged in advance of the stock feeding and cutting mechanisms, and an independent horizontally adjustable work guide and punch block arranged in line with said feeding and cutting mechanisms.

8. In a machine for cutting corks from a rectangular strip of stock, the combination of means for supporting and intermittently feeding the stock longitudinally through the machine, a reciprocating cutter and a cutter-block co-operating therewith for cutting corks transversely from said stock as it is intermittently fed through the machine, a rotary cutting disk arranged out of alignment with and beyond said reciprocating cutter and in the path of movement of the stock, means for adjusting the rotary cut-

ting disk with relation to the reciprocating cutter, a power shaft, and connections between said shaft and the feeding and cutting mechanisms and said rotary cutting disk for simultaneously operating said parts, whereby the corks may be successively cut from the stock by said reciprocating cutter and a solid strip of cork subsequently trimmed from the edge of the thus previously cut stock by the rotary cutting disk

outside of the spaces formed by cutting the corks from the stock.

In testimony whereof I have hereunto set my hand this second day of December A. D. 1913.

PETER CODINA.
